His Attorney.

UNITED STATES PATENT OFFICE.

BEVERLY L. STEMMONS, OF CHARLOTTE, NORTH CAROLINA, ASSIGNOR TO GENERAL ELECTRIC COMPANY, A CORPORATION OF NEW YORK.

PROTECTIVE DEVICE.

1,396,538.

Specification of Letters Patent.

Patented Nov. 8, 1921.

Application filed May 20, 1918, Serial No. 235,447. Renewed July 20, 1921. Serial No. 486,186.

To all whom it may concern:

Be it known that I, BEVERLY L. STEMMONS, a citizen of the United States, residing at Charlotte, in the county of Mecklenburg, State of North Carolina, have invented 5 certain new and useful Improvements in Protective Devices, of which the following is a specification.

My invention relates to protective devices 10 and more particularly to devices for the protection of electrical conductors from conditions of lightning disturbances, transients and other over-voltage phenomena.

The object of my invention is to provide 15 a device which is operative to relieve a conductor from excessive voltage conditions caused by transients, surges and similar phenomena, and more specifically to provide a spark gap device for use in outdoor 20 service, which will discharge at its dry arc-over voltage setting independent of weather conditions with a very short time delay between the application of arc-over voltage and the discharge across the device, and 25 which is, in general, an improvement on similar devices of this nature heretofore known in the art.

It is known, as described in U. S. Letters Patent #1,232,467, granted to Frank W. 30 Peek, Jr., that a protective or spark gap device which comprises two coöperating electrodes having their proximal surfaces in the form of surfaces of revolution, such as two spheres, and separated by a certain distance relative to the radius of the spheres, forms a spark gap having a substantially uniform dielectric field. When arc-over voltage occurs across such a gap, there is a 35 minimum time delay between the occurrence 40 of arc-over voltage and the rupture of the dielectric or the discharge across the gap, that is, there is no formation of brush discharge or corona prior to the discharge of the gap to introduce a time delay. A sphere 45 gap so proportioned is very fast and serves quickly to relieve the conductor to be protected from all excessive voltage conditions and particularly surges of steep wave front. An arrester comprising a gap is better 50 adapted for outdoor service if the gap is protected from the weather, as weather conditions, such as rain, snow and ice collects on the electrodes and serve to lower the voltage at which an arc-over will occur as 55 the arc-over voltage of a gap under wet conditions, or the wet arc-over voltage is

less than the arc-over under dry conditions or the dry arc-over voltage.

According to my invention, I utilize the speed of the properly proportioned sphere 60 gap, together with means whereby an arrester comprising such a gap may be operated outdoors and controlled by its dry arc-over voltage setting and hence at maximum efficiency. I obtain the dry arc-over 65 setting by providing an arrester having two spark gaps in series, one gap being protected from conditions of the weather and controlling the complete breakdown of the arrester and the other gap unprotected, in combination 70 with a third gap of the horn type which is so related to the series gaps to take the arc formed and cause its rapid extinguishment.

The novel features which I believe to be 75 characteristic of my invention will be definitely indicated in the claims appended hereto, while the features of construction and method of operation will be understood by reference to the following description taken in connection with the accompanying 80 drawing which shows, in perspective view, a protective device embodying the features of my invention.

As shown in the drawing, the protective device of my invention comprises two co- 85 operating electrode members 1 and 2, spaced apart and diverging from each other to form a horn gap 3. The electrode, or horn member 1, is mounted on an insulating member 4 and adjustably supported thereon by 90 a clamping means or member 5. The horn member 1 is adapted to be connected to one terminal of the arrester, and preferably to the conductor to be protected, when the device is connected between a conductor and 95 ground, by means of a suitable connection such as terminal member 6. The coöperating electrode, or horn member 2, rests upon and in engagement with a protecting hood or umbrella-shaped member 7 preferably of 100 metal. The umbrella-shaped electrode, or member 7, is insulated and, for this purpose, preferably supported by an insulator 8. The umbrella electrode may be of any suitable configuration, but in the preferred form, 105 I desire to make this member substantially cylindrical, closed at the top and with its lower edge 9 rolled over or otherwise shaped to eliminate any sharp edges and thereby produce a more uniform dielectric field. 110

Adjustably mounted beneath the umbrella electrode 7 and protected thereby, is an elec-

trode member 10 having a configuration of a surface of revolution and preferably a sphere. This electrode is spaced away from the inner surface of the umbrella electrode 5 and coöperates therewith to provide a spark gap 11 which is protected from the weather and which I desire to designate the main gap. The sphere electrode 10 is adapted to be connected to the other terminal of the arrester and preferably to ground when the arrester is connected between line and ground. As one convenient means of mounting the spherical electrode 10, I have shown the insulator 8, with the umbrella electrode 7, supported by a conducting member 12 which is preferably in the form of a metal strip of sufficient thickness to enable the insulator 8 with its umbrella member to be supported rigidly. This 10 conducting member 12 is adapted to be connected to one terminal of the arrester and I adjustably mount upon this conducting member 8 and in conductive relation therewith, the spherical electrode 10.

20 Adjustably mounted upon the horn electrode 1 is an electrode member 13 consisting of a surface of revolution and preferably a sphere which, in the form shown, is slideable on the horn member 1 and adapted to co-operate with the outer surface of the umbrella electrode 7 to form a spark gap 14 which is in series with the main gap 11 but unprotected from weather conditions. I prefer to designate the spark gap 14, the 25 auxiliary spark gap. It will be observed that the space between the two spherical electrodes 10 and 13 is divided into two gaps 11 and 14 in series by the common electrode or umbrella 7, one gap 14 being unprotected 30 and the other gap 14 being protected by the umbrella 7. When a complete discharge of the gaps 11 and 14 takes place, the horn electrodes 1 and 2 take the arc and it rises 35 quickly on the horns and is extinguished.

40 The horn gap 3, main gap 11, and auxiliary gap 14 may have various relations, but for most efficient results I prefer to adjust auxiliary gap 14 for a dry arc-over voltage of approximately 75% of the arc-over voltage of the main gap 11 and horn gap 3 for a normal frequency arc-over voltage 50 10% higher than that of gap 14.

The dry arc-over voltage setting of main gap 11 determines the complete gap spark-over. With this arrangement static spark-over will not occur under normal dry operating conditions, but if the potential is increased gap 14 will first arc-over and if the potential is still further increased complete 55 spark-over of the gaps 11 and 14 will occur.

What I claim as new and desire to secure by Letters Patent of the United States, is:—

1. In a protective device, two coöperating electrodes having their proximal surfaces 60 in the form of surfaces of revolution and

spaced apart to form a spark gap, of an umbrella member forming a common electrode between said coöperating electrodes and partially inclosing one of said electrodes.

2. In a protective device, two coöperating electrodes having their proximal surfaces spherical and spaced apart to form a spark gap, a third electrode member coacting with said coöperating electrodes to form two spark gaps in series and shaped to partially inclose one of said electrodes to protect one of said spark gaps from the weather.

3. In a protective device, the combination of an umbrella member, of an electrode beneath said umbrella and an electrode outside said umbrella coöperating therewith to form two spark gaps in series, one of said gaps being protected from the weather and the other gap being unprotected.

4. In a protective device, an insulated metallic umbrella member, an electrode beneath said umbrella and spaced away from the same to provide a spark gap having an arc-over voltage independent of weather conditions, a coöperating electrode outside said umbrella and spaced away from the same to provide a second spark gap.

5. In a protective device, the combination with two coöperating electrodes separated to form a spark gap, of a conducting hood member extending into said gap and partially inclosing one of said electrodes to provide a main spark gap between said hood member and the inclosed electrode and an auxiliary spark gap between said hood member and the other of said electrodes.

6. In a protective device, the combination with the coöperating electrodes having their proximal surfaces spherical and spaced apart to form a spark gap, a third electrode member extending between said coöperating electrodes and shaped to partially inclose one of said electrodes, and means for extinguishing arcs formed between said electrodes.

7. In a protective device, the combination with an umbrella member, of an electrode beneath said umbrella and an electrode outside said umbrella coöperating therewith to form two spark gaps in series, and coöperating horn gap members in conductive relation with said outside electrode and said umbrella.

8. A protective device comprising an umbrella electrode, a coöperating electrode beneath said umbrella and spaced away from the same to provide a spark gap, an arcing horn carried by said umbrella electrode, a coöperating arcing horn, and a third electrode carried by said coöperating horn and coöperating with said umbrella to form a second spark gap.

In witness whereof, I have hereunto set my hand this 13th day of May, 1918.

BEVERLY L. STEMMONS.
